UNITED STATES PATENT OFFICE.

THOMAS M. ATKINSON, OF MILLTOWN, NEW JERSEY, ASSIGNOR TO THE ROYSTON PAPER COMPANY, OF MILLTOWN, NEW JERSEY, A CORPORATION OF NEW JERSEY.

COLORED SHEET MATERIAL AND METHOD OF PRODUCING THE SAME.

Application filed September 9, 1925. Serial No. 55,354.

My invention aims to provide an improved colored web or strip of sheet material, more particularly paper, and method or process of producing the same, the present 5 invention being an improvement upon the method and article disclosed in my Patent 1,475,923, dated November 27, 1923.

In the drawings illustrating one form of apparatus for practicing my method or process and showing also one form of colored sheet material embodying my invention:

Fig. 1 is a view partly in side elevation and partly in cross section;

Fig. 2 is a plan view showing a portion of 5 an untreated strip of material;

Figs. 3 and 4 are plan views illustrating intermediate steps in the process;

Fig. 5 shows one form of the finished product.

0 In my patent above mentioned there is disclosed and claimed an apparatus for and method of producing colored sheet material, such as paper and particularly that type of colored paper previously produced by hand 5 dipping and commonly known as colored nature papers. The roll of untreated paper in said patent may be white or colored but preferably is of uniform color throughout and the resulting paper is also uniform in shade and tone throughout its entire length.

In accordance with my present invention the sheet material or paper is given a basic or body color which is uniform but in which appear any desired configurations in different or contrasting color or colors in or apparent through the basic color. The designs or configurations may be variously applied prior to the dyeing operation and in any suitable manner, as by printing, lithographing, photogravure, stamping, or the like, and in Figs. 3 and 4 I have illustrated one method of pre-forming said colored areas.

In Fig. 2 I have represented a portion of a strip or web of plain sheet material 6, herein paper, which may be white or any other suitable color. Said plain colored, or uncolored web is passed between a pair of printing rolls, of which the upper roll 35 appears in Fig. 3. Said rolls are adapted to print

in color upon one or both faces of the strip material, the color being applied to form any desired configuration or design, such as the irregular colored areas A, A, etc., indicated by the stippling in Figs. 3, 4 and 5. 55 Thereafter, the paper or other material may be passed between a second pair of printing rolls, one of which is indicated at 36 in Fig. 4. Said second rolls place upon the paper configurations or areas B, B, etc., indicated in solid black in Figs. 4 and 5. Preferably said configurations or designs, which are of a color contrasting with that previously applied, are formed of bronze, gold, silver, or other metallic or lustrous coloring materials or their substitutes. In some places the metallic or lustrous areas may overlie the colored sections previously applied, while in other places they may be applied directly to the material, the arrangement and form of the various configurations being in accordance with the whim of the individual manufacturer. As in Fig. 3, the configurations may be imposed on both faces of the material, but ordinarily one face only is configured, and if desired only the metallic or lustrous colored areas may be applied.

The strip material or paper with the configurations imposed, either in a single and preferably metallic color or in a plurality of colors, may be rewound into roll form or may be passed directly from the printing or other color applying means to the dyeing apparatus. The latter is preferably of the type disclosed and claimed in my said patent 75 and herein sufficiently illustrated to afford a complete understanding thereof.

Referring to Fig. 1, said apparatus includes a frame-work 1 comprising the spaced uprights 2, 2, etc. At the left said uprights support a holder or unwinding roller 3 upon which the paper previously prepared, as in the manner above described, is rotatably supported, when in roll form, or across which it passes if it is to be passed directly from the printing or design applying apparatus to the bath of dye. To the right of said roller 3 said uprights support a series of stretcher or ironing rollers 5, 5, the strip or run of material 6 being passed respectively under 95 100

and over alternate rollers. Beyond the right end roller 5 is a dye tank 7 upon a suitable platform 8 supported upon the framing. The strip of material passes downwardly 5 into the bath of dye in said tank, passing beneath a roller 9 journaled in the side walls of the tank.

The bath through which the run of paper is drawn preferably is composed of aniline 10 or other dye dissolved in a suitable solvent, such as alcohol. To the solution may be added a small proportion of glycerine, approximately five per cent, to give the desired flexibility to the colored paper.

15 Upon emerging from the tank the dyed material is passed between a pair of adjustable pressure rollers 10, 11, the pressure of which may be regulated to control the amount of dye to be squeezed out and returned to the tank along the apron 19.

20 The web of material or paper is then dried, preferably by being passed through a hot air box or oven 20. The air in said oven is maintained at a constant heat by 25 the inflow of heated air from the inlets 21, heated air being supplied from a suitable source, not shown. The oven is provided in its upper surface with a suitable outlet and exhaust pipe 22 for conducting away 30 the foul air and gases. The colored paper or web travels continuously through the oven and passes above a roller 23 journaled in the rear wall thereof. The extent and rate of travel and the degree of heat are 35 such that the paper will have been entirely dried before arriving at said roller 23. It is thus apparent that the moist dyed web after leaving the pressure rollers 10 and 11 has no contact with any supporting or other 40 surface until said paper has been thoroughly dried.

45 Beyond the drying oven the run of dyed sheet material is passed through a series of cooling chambers 24. The air in said chambers may be kept in motion by a blower 33 to aid in the cooling. When such blower is employed the chambers 24 desirably are provided with inter-communicating openings (not shown) in the lower portions 50 thereof, the outer wall of the outermost chamber 24 having a similar opening for the exit of the cooling air. Near the top and the bottom of each of said cooling chambers are rotatably mounted the cooling 55 chamber rollers 25. The strip of material is festooned about said cooling rollers through successive chambers and is finally led out and wound upon the rewinding roller 26 rotatably mounted in a suitable stand- 60 ard 27.

65 A suitable source of power such as an electric motor 28 is provided, having a driving connection, shown as a belt 29, with a pulley upon the shaft of the lower pressure roller 11. Said pulley 30 also supports one

end of a belt 31 leading to the rewinder 26 and passing about a pulley 32 coaxial with the same. The rewinder and the pressure rollers are thus driven at the same relative speed causing the run of sheet material to 70 be drawn evenly at a constant rate past the ironing rollers 5, through the bath of dye, between the pressure rollers, through the drying oven and subsequently through the cooling chambers until rewound upon the 75 roll 26 in finished condition. Obviously the dyed and cooled run of paper or other sheet material may be cut into sheets or otherwise packaged after leaving the cooling chambers, if not desired in roll form. 80

85 The resulting product is a web of sheet material having a basic or body color of uniform hue and tone but in which appear designs or configurations blending together in a singularly striking and attractive manner. In Fig. 5, illustrating a portion of the finished product, the horizontal lines indicate a uniform color received from the dye. The effect is particularly pleasing 90 where metallic or lustrous coating materials are included in the pre-applied designs or configurations, as above disclosed, the same being applied prior to the dyeing operation. The dye modifies the sheen of said coating materials, while still permitting them to show in or through the basic color, presenting patches or mottled portions of lustrous and changing appearance as the light may strike them differently. In addition the dye acts as a preservative coating 95 or binder to "fix" said metallic materials which are thus prevented from readily rubbing off from the surface of the finished material. The decorative feature of said material is thereby made permanent while 100 its heretofore objectionable characteristics, such as its proneness to rub off and to soil contacting objects, are obviated. Paper or other sheet material produced in accordance with my process above described is particularly useful for forming coverings, 105 wrappers, and the like.

110 My invention is not limited to the embodiment thereof herein shown and described.

Claims:

1. As an article of manufacture, a web of colored paper suitable for covering and like purposes, said paper having imposed upon at least one surface thereof a plurality of configurations including metallic or other lustrous coating material pre-applied beneath a dye of uniform hue and tone, whereby said paper is given a single or basic color in which said configurations are blended and fixed. 115

2. That method of producing colored paper suitable for covering, binding and like purposes which comprises printing or otherwise forming on one or both surfaces of said web configurations in a metallic or 120

lustrous coloring material optionally in combination with other configurations of one or more non-metallic colors contrasting with the color of the untreated paper, mounting said configurated paper in position for feeding, drawing the same out into a web, conducting said web through a bath of dye differ-

ing in color from that of any of the pre-applied configurations, and subsequently heat drying, and cooling said web preliminary to packaging for storage or shipment. In testimony whereof, I have signed my name to this specification.

THOMAS M. ATKINSON.
